[57] CLAIM

The ornamental design for a golf putter head, as shown and described.

DESCRIPTION

FIG. 1 is a perspective view showing the front side, right side (toe), and top of the ornamental design;

FIG. 2 is a top plan view of the same;

FIG. 3 is a front elevational view of the same;

FIG. 4 is a bottom view of the same;

FIG. 5 is a right side (toe) elevational view of the same;

FIG. 6 is a back elevational view of the same; and,

FIG. 7 is a left side (heel) elevational view of the same.

That broken line showing of a fragmented shaft is for illustrative purposes only and forms no part of the claimed design.
